DESIGN FOR A COPYING CAMERA SUPPORT

Alvin E. Schubert, Rochester, N. Y., assignor to Eastman Kodak Company, Rochester, N. Y., a corporation of New Jersey

Application July 16, 1940, Serial No. 93,676

Term of patent 14 years

To all whom it may concern:

Be it known that I, Alvin E. Schubert, a citizen of the United States, residing in Rochester, county of Monroe, and State of New York, have invented a new, original, and ornamental Design for a Copying Camera Support, of which the following is a specification, reference being had to the accompanying drawing, forming part thereof.

In the drawing:

Fig. 1 is a side elevational view of copying camera support showing my new design.

Fig. 2 is a top plan view of the same.

I claim:

The ornamental design for a copying camera support, as shown.

ALVIN E. SCHUBERT.
